UNITED STATES PATENT OFFICE

171,931

FISHLINE SINKER

Major E. Daves, El Sobrante, Calif.

Application December 21, 1953, Serial No. 28,143

Term of patent 14 years

(Cl. D31—4)

To all whom it may concern:

Be it known that I, Major E. Daves, a citizen of the United States, residing at El Sobrante, county of Contra Costa, State of California, have invented a new, original, and ornamental Design for a Fishline Sinker, of which the following is a specification, reference being had to the accompanying drawings, forming a part hereof, wherein,

I claim:

The ornamental design for a fishline sinker, substantially as shown.
